UNITED STATES PATENT OFFICE.

JAMES E. MACGREGOR, OF KANSAS CITY, MISSOURI.

APPARATUS FOR PERMANENTLY WAVING OR CURLING HAIR.

Application filed March 11, 1926. Serial No. 93,895.

My invention relates to improvements in apparatus for permanently waving or curling hair.

One of the objects of my invention is to provide a novel apparatus for permanently waving or curling hair, which is effective and quick in operation, and with which the hair is not liable to be overheated and burned or otherwise injured.

10 A further object of my invention is to provide a novel apparatus of the kind described, which is simple, portable, durable, not liable to get out of order, which will quickly wave the hair and cool the same, 15 which can quickly be adjusted for the treatment of the hair of persons of different statures, and with which a complete permanent wave may be made in a very short time without liability of burning the hair or person of 20 the subject operated upon.

My invention provides still further a novel steam boiler adapted for the particular use in view.

25 My invention provides also a novel hair heating form.

The novel features of my invention are hereinafter fully described and claimed.

In the accompanying drawings, which 30 illustrate the preferred embodiment of my invention adapted for carrying into effect my improved method,

Fig. 1 is a front elevation of my improved apparatus, partly broken away.

Fig. 2 is an enlarged central vertical section, 35 partly broken away, of my improved apparatus.

Fig. 3 is a section on the line 3—3 of Fig. 2.

40 Fig. 4 is a fragmental elevation of one side of the condensing receptacle.

Similar reference characters designate similar parts in the different views.

1 designates the shell of the steam boiler, 45 which, as shown, is spherical, and is provided with a horizontal partition 2, which forms in the shell 1 a lower heating chamber 3 and an upper steam and water containing chamber 4.

50 In the chamber 3 is provided suitable heating means, which may comprise an ordinary electrical heating element 5, the terminals 6 of which are connected to an ordinary plug 7 adapted for insertion in an ordinary electric socket, not shown.

The steam chamber 4 is provided with 55 a valved inlet adapted to communicate with the atmosphere for receiving water and for the discharge therethrough of air. Such inlet may comprise a tube 8 disposed above the level of the water 9 in the boiler and having 60 a lateral opening 10 adapted to be closed by a cap 11 revolvably fitted on and closing the end of the tube 8.

The shell 1 of the boiler may be provided 65 above the water level with as many steam outlets as desired, comprising externally threaded tubes 12 adapted to have respectively fitted on them, when not in use, screw caps 13, and also adapted to have fitted respectively on them flexible conductors, 70 which are respectively fitted on tubes 14, similar to the tubes 12, which are provided on the spherical shell 15 of a condensing receptacle.

One side of the shell 15 is provided with 75 a valved air inlet comprising an opening 16 adapted to be closed by a valve 17 rotatably mounted on the shell 15.

The flexible conductors above referred to 80 each consists of two end sections 18, 19 which are respectively fitted in one end and over the other end of a heat conductive tube 20, preferably plated copper or aluminum, which serves as a form around which the hair to be waved is wound, the tube 20 85 having suitable peripheral projections, such as annular flanges 21, with which the hair may be engaged and held.

The sections 18 and 19 may be ordinary 90 hose in which for stiffening purposes may be inserted coiled wires 22, which are sufficiently soft and pliable as to retain the sections 18 and 19 in the forms in which they are disposed.

Extending through the shell 15 is a horizontal rotary armature shaft 23 of an electric motor 24, which is supported on a bracket 25 fastened to the exterior of the shell 15. Mounted on the shaft 23 is a centrifugal fan comprising a hub 26 fastened on the shaft and to which are fastened radial blades 27.

The lower side of the shell 15 is provided 105 with a drain tube 28, having mounted in it a butterfly valve 29. The water from steam condensation in the shell 15 may be withdrawn from the shell through the tube 28.

As shown in Fig. 1 the boiler shell 1 and

the shell 15 of the condensing receptacle may be vertically adjustably supported on two portable stands respectively. Each of said stands may comprise a vertical tube 5 30 mounted at its lower end upon a base member or foot 31, the tube 30 having vertically slidably in it a rod 32, which is adapted to be engaged with and held in an adjusted position by a set screw 33 in the tube 10 30. The two rods 32 have their upper ends respectively secured to the lower sides of the shells 1 and 15.

In the operation of the invention, water 9 is placed in the chamber 4 through the 15 opening 10. The plug 7 is connected with a convenient socket of a lighting system and the current is turned on by means of a switch 34 carried by the plug 7.

The subject to be operated upon is then 20 seated between the stands, and the rods 32 adjusted to suit the stature of the subject, when seated.

The hair is then wound on the tubular form sections 20 and is engaged with the 25 projections 21, and held in such wound condition by any suitable means, as by cloths or paper.

The steam formed in the chamber 4 passes 30 through the tubes 20 and heats the air so that in a few minutes it becomes set or formed permanently. As the hair can not be heated to a temperature above the temperature of the steam, there is no liability 35 of its being burned or injured by the heat, and, the walls of the steam conductors being imperforate, the steam does not contact with the hair, and the latter is not affected by the moisture of the steam employed to heat the hair.

40 The steam passes into the shell 15 where it is condensed, the valve 17 being closed. The water may be drawn off through the drain tube 28. The valve or cap 11 is closed when steam is being made in the chamber 4.

45 After the hair has been heated sufficiently, the current is shut off from the heating element 5, the cap valve 11, is opened, as is the valve 17 and the motor 24 is operated to revolve the fan blades 27, whereby cold air is drawn into the shell 15 and is forced 50 through the flexible conductors 18, 19 and 20 into the steam chamber 4, and thence through the opening 10 to the atmosphere. The cold air passing through the tubes 20 quickly cools them, thereby also quickly 55 cooling the hair which is thereupon. After the hair has been cooled, it is removed from the tubes 20, which can be done by slipping the tubes 20 out of the tubes 19. By having 60 a sufficient number of the flexible conductors, the entire waving operation on the subject may be completed at one time and in a very short period.

65 I do not limit my invention to the structure and specific steps shown and described,

as many modifications, within the scope of the appended claims, may be made without departing from the spirit of my invention.

What I claim is:—

1. In an apparatus of the kind described, 70 a tubular heat conductive form around which the hair is adapted to be wound, means for passing steam through said form, and means for passing a cooling fluid through said form. 75

2. In an apparatus of the kind described, a steam boiler, and a steam conductor connected therewith having a heat conductive section around which hair is adapted to be wound, the wall of said conductor being imperforate and arranged to hold the steam 80 therein out of contact with the hair. 85

3. In an apparatus of the kind described, a steam boiler, a steam condensing receptacle having an air inlet and a valve for closing 85 said inlet, a steam conductor connecting said boiler and said receptacle having a heat conductive section around which hair is adapted to be wound, and a fan in said receptacle adapted, when revolved, to force 90 air through said conductor. 95

4. In an apparatus of the kind described, the atmosphere, a steam condensing receptacle, and steam conductors connecting said boiler and said receptacle, each conductor 95 having a heat conductive section around which hair is adapted to be wound and heated. 100

5. In an apparatus of the kind described, 100 a steam boiler having a steam and water containing chamber provided with a valved opening communicating, when open, with the atmosphere, a steam condensing receptacle having a valved air inlet, steam conducting means connecting said steam chamber with said receptacle provided with heat conductive means around which hair is adapted to be wound and heated, and means for forcing air from said receptacle through 105 said conducting means. 110

6. In an apparatus of the kind described, a steam boiler, a steam condensing receptacle, steam conducting means connecting said boiler and said receptacle having heat conductive means around which hair is adapted 115 to be wound and heated thereby, and two stands respectively supporting said boiler and said receptacle. 120

7. In an apparatus of the kind described, a steam boiler, a steam condensing receptacle, steam conducting means connecting said boiler and said receptacle having heat conductive means around which hair is adapted to be wound and heated thereby, and two stands on which said boiler and said receptacle are respectively vertically adjustably supported. 125

8. In an apparatus of the kind described, a steam boiler, a steam condensing receptacle, flexible steam conductors connecting said 130

boiler and said receptacle, each conductor having a heat conductive section around which hair is adapted to be wound and heated thereby, and two stands respectively supporting said boiler and said receptacle.

9. In an apparatus of the kind described, a steam boiler having a valved opening adapted to communicate with the atmosphere, a steam condensing receptacle having a valved opening adapted to communicate with the atmosphere, flexible steam conductors connecting said steam boiler and said receptacle, each conductor having a heat conductive section around which hair is

adapted to be wound and heated thereby, a 15 rotary fan in said receptacle adapted, when rotated to force air from said receptacle through said conductors into said boiler, a motor connected with and adapted to rotate said fan, and an electrical heating element 20 in said boiler adapted to heat the water in said boiler and provided with means for operative attachment with an electrical current supply source.

In testimony whereof I have signed my 25 name to this specification.

JAMES E. MACGREGOR.
